Inventor:

Isaac U. Chubbuck

UNITED STATES PATENT OFFICE.

ISAAC Y. CHUBBUCK, OF ROXBURY, MASSACHUSETTS.

FAN-GOVERNOR FOR STEAM-ENGINES.

Specification of Letters Patent No. 26,414, dated December 13, 1859.

To all whom it may concern:

Be it known that I, ISAAC Y. CHUBBUCK, of Roxbury, in the county of Norfolk and State of Massachusetts, have invented a new 5 and useful Improvement in Fan-Governors for Steam-Engines and other Motors; and I do hereby declare that the following is a full, clear, and exact description of the same, reference being had to the accompanying 10 drawing, forming part of this specification, in which—

Figure 1, is a front view of a governor with my improvements. Fig. 2, is a side view of the same partly in section. Fig. 3, 15 is a back view of the spring box or weight pulley.

Similar letters of reference indicate corresponding parts in the several figures.

My invention consists in a novel mode of 20 combining the spindle of a fan governor with the stem of the regulating valve whereby the governor and valve are brought together in a very compact form without arranging the governor upon the valve spindle 25 and thereby tending to draw the said spindle out of truth and so interfering with the proper operation of the valve.

To enable others skilled in the art to make and use my invention I will proceed to 30 describe its construction and operation.

A, is the valve box and B, the valve stem. I have not represented the valve as it may be of any of the kinds commonly employed as regulators, but I generally use one of the kind 35 commonly known as the register valve. On the top of the valve box there is provided a stationary bearing L, for the main spindle C, of the governor which is arranged parallel with the valve stem. This spindle has 40 fast upon it near its rear end a driving pulley G, and near its front end a spur gear b, and is fitted with a loose sleeve D, close behind the said gear b. This sleeve in which the spindle C, is capable of turning freely, 45 is furnished with a crank like arm E, in which is secured a stud a, upon which the hub F, of the fan is fitted to rotate freely. The said arm E, has a toothed arc i i formed upon or attached to its lower extremity and 50 the teeth of this arc gear with a toothed sector H, on the valve stem B. The sleeve is represented in the drawing provided with a fast pulley I, from which to suspend a weight by a cord or chain in such a manner 55 that the said weight would exert a tendency

to turn the sleeve in the opposite direction to that indicated by an arrow e, on the gear b, in Fig. 1, in which the main spindle is driven and by means to keep the valve open by the action of the teeth of the arm E, 60 upon the sector H. Instead of the weight, however, I have represented a coiled spring J, see Figs. 2, and 3, applied to produce the same effect upon the sleeve said spring being arranged within a stationary box K, secured 65 to the bearing L, and having one end fast to the said box and the other end fast to the sleeve. As the movement produced by this spring or weight need not be very considerable stops c, c, are provided on the sleeve or 70 pulley on opposite sides of a fixed stop d, on the box K, the stops c', preventing the valve being moved beyond the position in which it is wide open and the stop c, preventing it moving beyond the position in which it is 75 closed. The hub F, of the fan has secured to it a spur gear f, gearing with the gear b, of the main spindle.

By the revolution of the main spindle C, of the governor in the direction of the arrow e, derived from the steam engine or other motor, the gears b, f, are caused to produce a revolution of the fan in the opposite direction indicated by the arrow h, in Fig. 1. The resistance of the atmosphere to the revolution of the vanes M, M, of the fan tends 80 to turn the crank arm E, in the direction of the arrow g, (Fig. 1) that is to say the opposite direction to that in which the spring J, or weight tends to turn the said arm, such 85 resistance acts through the said arm E, on the sector H, and hence to close the valve, and this tendency becomes greater or less as the velocity of the fan is increased or diminished 90 by an increased or diminished speed of the engine. By thus separating the valve stem from the main spindle of the governor attaching the crank arm which carries the fan to a loose sleeve and gearing 95 the governor and valve stem by teeth on the said crank arm and a sector on the stem, the 100 governor and valve are combined in a more compact form than when the crank is attached directly to the valve stem or spindle, and the valve is relieved by the injurious 105 action to which it is subjected by the rocking action of the weight of the governor on its stem or spindle, and besides this provision is made for giving the valve any 110 amount of movement with a given move-

ment of the crank arm, by the use of a toothed arc and sector of suitable relative radii.

I do not claim generally attaching the 5 crank arm E, which carries the fan to a sleeve or spindle separate from the valve stem as such a mode of applying the said arm has been in use ever since the year 1842, in the governor invented by Stillman E. 10 Chubbuck and now extensively used in the eastern States; but

What I claim as my invention and desire to secure by Letters Patent, is—

Combining the main spindle C, of the fan governor with the stem or spindle B, of the 15 valve by means of a toothed arc formed upon or attached to the extremity of the crank arm which carries the fan, and a toothed sector upon the valve stem, the said crank arm being attached to a sleeve fitted to the 20 spindle C, and the whole being otherwise arranged substantially as herein described.

ISAAC Y. CHUBBUCK.
